Elkins, W. Va.

Application April 14, 1952, Serial No. 282,202

3 Claims. (Cl. 84—274)

This invention relates to violin construction, the primary object of the invention being to provide a violin wherein the number of strings is increased appreciably over the conventional four string violin construction.

The primary object of the invention is to provide a violin or similar stringed instrument, which is so constructed that the volume of the instrument will be substantially increased, without sacrificing mellowness of tone.

An important object of the invention is to provide a violin having groups of strings arranged directly under the playing strings of the violin, which groups of strings are tuned in sympathy with the conventional strings of the violin to produce chords incident to the sympathetic vibrations of the groups of auxiliary strings of the instrument, when the usual four strings of the violin are played.

A further object of the invention is the provision of a violin having a hollow neck that is of a length to extend throughout the length of the violin body, within the body, providing a sound box within the body of the violin, increasing the tone volume of the instrument, and at the same time appreciably increasing the strength of the violin structure to withstand the increased strain directed thereto, due to the tension of the increased number of strings.

A still further object of the invention is to provide a violin wherein the strings are arranged to facilitate the playing of the violin in the upper positions, with an increased volume.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

Referring to the drawings,

Figure 1 is a plan view of a violin, constructed in accordance with the invention.

Fig. 2 is a side elevational view thereof.

Fig. 3 is a fragmental perspective view on an enlarged scale, illustrating the hollow neck constituting an auxiliary sound box.

Fig. 4 is a sectional view taken on line 4—4 of Fig. 2.

Fig. 5 is a sectional view taken on line 5—5 of Fig. 1.

Referring to the drawings in detail, the reference character 5 indicates the body portion of the violin, which is generally of the same construction as violins now in common use, with additional means including the post 6 which has its upper and lower ends so arranged with respect to the upper and lower walls of the body, that the body portion of the violin will be braced at a point in proximity to the bridge of the violin, which is indicated by the reference character 7.

Disposed longitudinally of the upper wall of the body, and arranged on the side of the body opposite to the post 6, is the G-bar or brace 8 which tends to brace the upper wall of the body portion, but at the same time permits of the necessary vibrations to produce a true tone.

2

Forming an important feature of the violin, is the neck, which is shown more clearly by Fig. 3 of the drawings, the neck being indicated by the reference character 9. As shown, the neck 9 is hollow throughout its length, and is provided with the extension 10 which extends within the body portion of the violin, throughout the length of the violin, the upper and lower walls of the extension 10 being spaced from the upper and lower walls respectively of the body portion of the violin to permit of the necessary vibrations of the walls of the extension 10. The top of the extension 10 is formed with openings 11, which openings are disposed adjacent to the ends of the extension, so that sound waves produced by the vibrating strings of the violin may pass into an opening, through the auxiliary sound box formed by the extension 10, and exhaust through the opening at the opposite end of the extension or sound box.

The apron of the violin is indicated by the reference character 12 and affords means for securing the violin strings to the end of the body portion, as clearly shown by the drawings. The four playing strings of the violin are indicated by the reference character 13, and these strings extend over the bridge 7, and pass to the keys 14, which keys are operated in the usual and well known manner in tuning the instrument.

The reference character 15 indicates the auxiliary strings of the violin, the auxiliary strings of the violin passing through the openings 16 formed in the bridge 7, supporting the strings in spaced relation with the upper wall of the violin.

These auxiliary strings 15 are connected with the keys 17 that are supported by the head in such a way that the keys 17 may be operated to tune the auxiliary strings of the instrument, which are arranged in three groups of four and tuned to provide identical chords.

When playing the violin, the playing strings are manipulated in the same manner as the usual violin, and since the auxiliary strings are arranged in groups of four and are tuned to provide identical chords, it will be obvious that when the ordinary playing strings of the violin are being played, the sympathetic vibrations of the auxiliary chords, caused by the vibrations produced by the playing strings, will set up tones to appreciably increase the volume of the violin.

Due to the construction of the neck of the violin, which includes the extension 10, an auxiliary sound box is provided within the body portion, to pick up the tones created by the vibrations of the auxiliary strings, thereby reducing the usual harsh tones produced by wire strings, to mellow tones.

It might be further stated that because of the G-bar or brace 8, together with the post 6, the top and bottom walls of the body of the violin are securely braced against the severe pressure directed thereto, by the great number of strings forming a part of the violin.

Having thus described the invention, what is claimed is:

1. In a violin, a body, a hollow neck having a head formed at one end thereof, secured to the body, said neck including a hollow extension extending within the body throughout the length of the body, said extension having openings in the top thereof adjacent to the ends of the extension, providing a sound box within the body, and strings supported on the body secured to the body and head of said neck.

2. In a violin, a body, a hollow neck having a head, secured to the body, said neck including a hollow extension extending within the body throughout the length of the body, said extension embodying top and bottom and side walls spaced from the walls of the body, said extension having openings in the top wall thereof adjacent to the ends of the extension, providing a sound box within

the body, and strings supported on the body secured to the body and head of the instrument.

3. In a violin, a body, a hollow neck having a head at the outer end thereof, secured to the body, said neck including a hollow extension extending within the body throughout the length of the body, said extension having openings in the top thereof providing an internal sound box within the body, a G-bar secured to the inner surface of the top of the body and extending longitudinally of the body, a vertical post disposed between the top and bottom of the body, and wires secured to the body and head. 10
